UNITED STATES PATENT OFFICE.

JOSEPH WILLIAM POPE, OF BOSTON, MASSACHUSETTS.

FUEL-HEATING APPARATUS FOR INTERNAL-COMBUSTION ENGINES.

1,168,111.

Specification of Letters Patent. Patented Jan. 11, 1916.

Application filed April 3, 1915. Serial No. 18,928.

To all whom it may concern:

Be it known that I, JOSEPH WILLIAM POPE, a citizen of the United States, residing at Boston, in the county of Suffolk and 5 State of Massachusetts, have invented a new and useful Fuel-Heating Apparatus for Internal-Combustion Engines, of which the following is a specification.

The present invention appertains to means 10 for heating the gasoline or fuel which is supplied to the carbureter of an internal combustion engine, whereby the gasoline or fuel will be properly and thoroughly vaporized in the carbureter, and under all atmospheric conditions, in order that the maximum efficiency is derived from the fuel.

It is the object of the invention to utilize the hot water flowing from the water jackets of the cylinders as a medium for heating the 20 gasoline or fuel flowing to the carbureter, and to this end there is a unique combination or arrangement between the water circulating system and fuel supplying means of the internal combustion engine.

It is also within the scope of the invention to provide an apparatus of the nature indicated which is comparatively simple, compact and inexpensive in construction, which may be readily installed in various 30 automobile, marine or other internal combustion engines, and which in operation will be thoroughly practical and efficient.

The invention is illustrated in the accompanying drawing wherein the figure is 35 an elevation of apparatus applied to an internal combustion engine, portions being broken away, and the hot water reservoir being shown in section.

In the drawing, there is delineated an internal combustion engine 1, which is to be 40 taken as typical only, and the cylinders of which are connected to the intake manifold 2, which in turn is connected to the carbureter 3. A copper or similar fuel or gasoline pipe 4 extends from the carbureter 3 to the fuel or gasoline supply tank 5 in the usual manner. The radiator is designated by the numeral 6, and the water jackets of the cylinders by the numerals 7.

In carrying out the invention, a portion 50 of the fuel supply pipe 4 is confined within a reservoir or container 8, that portion of the fuel pipe 4 within the reservoir 8 being coiled, as at 9. The reservoir 8 forms a portion 55 of the water circulating system of the engine, or a portion of the hot water con-

duit extending from the water jackets to the radiator, and to this end a hot water pipe 10 is connected at one end to the upper portion of one endmost water jacket 7, and is connected at its other end to one end of the reservoir 8. A pipe 11 is connected to the other end of the reservoir 8 and to the lower portion of the radiator 6, and a pipe 12 connects the radiator 6 and the other endmost water jacket 7. The usual pump (not shown) may be interposed in the water circulating system at any suitable point, for causing the water to circulate properly through the water jackets and radiator. The hot water reservoir 8 may be located at any suitable point between the engine and fuel tank, it being noted that the coiled portion 9 of the fuel pipe 4 is arranged contiguous to or within a portion of the hot water conduit which leads from the water jackets to the radiator.

In operation, the hot water from the water jackets 7 will flow through the hot water pipe 10 into the reservoir 8, and will flow around the convolutions of the coil 9 of the fuel pipe. From the reservoir 8 which is interposed in the hot water pipe connecting the water jackets and radiator, the water flows through the pipe 11 into the radiator, and the cooler water flows back into the water jackets by way of the pipe 12. The gasoline or other fuel in flowing through the coils 9 will be heated by the hot water, and the gasoline or fuel is thus prepared for ready and effective vaporization within the carbureter. The gasoline is thus vaporized more readily under all atmospheric conditions, and the present apparatus will eliminate the waste incident to the use 95 of cold gasoline or fuel, and the apparatus is of advantage for numerous other reasons which will suggest themselves to those versed in the art.

Having thus described the invention, what is claimed as new is:

The combination with the water jackets of an internal combustion engine, having a lower inlet and an upper outlet, a radiator having a lower inlet below said jackets, and a carbureter, of a cool water pipe connecting the radiator and the inlet of said jackets, a hot water reservoir disposed between the horizontal planes of the radiator inlet and the outlet of the jackets, a hot water pipe connecting the outlet of the jackets and one end of said reservoir, a pipe connecting the

other end of said reservoir and the inlet of the radiator so that the hot water flows downwardly from the jackets into said reservoir and thence downwardly from the reservoir into the radiator, and a fuel pipe connected to the carburetor and extending through said reservoir, said fuel pipe having a coil within the reservoir.

In testimony that I claim the foregoing as my own, I have hereto affixed my signature to in the presence of two witnesses.

JOSEPH WILLIAM POPE.
